UNITED STATES PATENT OFFICE

FREDERICK P. MICKELSON, OF DURHAM, NORTH CAROLINA, ASSIGNOR OF ONE-HALF
TO RAYMOND A. SORRELL, OF DURHAM, NORTH CAROLINA

DESIGN FOR A TELEPHONE CABINET

Application filed February 6, 1930. Serial No. 34,431. Term of patent 3½ years.

To all whom it may concern:

Be it known that I, FREDERICK P. MICKELSON, a citizen of the United States, residing at Durham, in the county of Durham and State of North Carolina, have invented a new, original, and ornamental Design for a Telephone Cabinet, of which the following is a specification, reference being had to the accompanying drawing, forming part thereof.

The figure is a front view in perspective of a telephone cabinet, showing my new design.

I claim:

The ornamental design for a telephone cabinet, as shown.

FREDERICK P. MICKELSON.
